UNITED STATES PATENT OFFICE.

GEORGE E. PICKUP, OF NEWARK, OHIO, ASSIGNOR TO THE WEHRLE COMPANY, OF NEWARK, OHIO, A CORPORATION OF OHIO.

GAS HOT-PLATE.

1,275,301.

Specification of Letters Patent. Patented Aug. 13, 1918.

Application filed December 28, 1914. Serial No. 879,278.

To all whom it may concern:

Be it known that I, GEORGE E. PICKUP, a citizen of the United States, residing at Newark, in the county of Licking and State 5 of Ohio, have invented certain new and useful Improvements in Gas Hot-Plates, of which the following is a specification.

One of the objects of this invention is to produce an improved gas hot plate which 10 is adapted to be folded or collapsed so as to occupy a minimum amount of space for shipment or storage. To this end the invention aims to provide an improved hinge connection between the top frame and the 15 end frames of the plate, and to provide improved means for bracing the end frames apart and for supporting the burners.

The invention also refers to an improved member which serves as a manifold or gas- 20 supply pipe, an attaching bracket therefor, and a flame guard.

In the accompanying drawings, Figure 1 is a front elevation of a hot plate embodying the features of my invention. Fig. 2 is 25 a longitudinal vertical section therethrough looking toward the rear. Fig. 3 is a longitudinal vertical section looking toward the front and showing the end frames in their folded position. Fig. 4 is a transverse or 30 front-to-rear section taken in the plane of line 4—4 of Fig. 1 and illustrating the manner of mounting the burners. Fig. 5 is a bottom plan view of the device in its folded position.

The preferred embodiment of the invention which is shown in the drawings, comprises a rectangular open top-frame 10 which is filled by the usual removable grids 11 for supporting cooking and other utensils. Gas plates of this character are 40 usually supported on four separate or independent legs which project downward and diagonally outward from the top frame. I have provided two end frames 12 which are 45 no wider than the top frame 10 and extend directly down therefrom, so that they require no greater supporting space than that defined by the top frame. The two end frames take the place of the four separate 50 legs heretofore employed and require less space for support than do the said legs.

Each of the end frames is hinged at its upper edge to the top frame to swing inwardly toward the other. The hinge connection comprises a suitable number of 55

U-shaped bearing members or loops 13 which may be screwed to the lower face of the top frame and are adapted to receive journals 14 formed on the top cross-bars of the end frames. Between said journals the 60 edge 15 of the said top bar forms a stop adapted to abut against the shoulder 16 on the top frame when the end frame is swung into vertical position. Offset lugs 17 at the 65 outer sides of the journals 14 are also adapted to abut against the top frame when the end frame is vertical. The outward swinging movement of the end frame is thereby positively limited. Each of the end frames has at its inner side two projecting 70 sockets 18 located one above the other. Either of the opposite pairs of these sockets is arranged to receive the ends of a burner-supporting rod 19, the lower sockets being 75 used for natural gas, and the upper sockets for manufactured gas, since the latter gas does not produce such a hot flame as natural gas. The rod 19 also acts as a brace to maintain the end frames 12 spread apart to the limit allowed by the stops previously 80 described.

The burners 20 are provided at their lower sides with pairs of lugs 21 adapted to straddle the rod 19. The stems 22 of the burners receive and rest upon stub-pipes 23 85 which are supported beneath the gas-supply pipe and are provided with the usual controlling valves 24.

A member 25 is cast to provide a pipe portion 26 and an integral plate portion 27 90 extending upwardly therefrom. The pipe portion 26 has a nipple 28 thereon to receive a flexible hose for supplying gas. The plate portion 27 has angular flanges or ribs 29 at its ends and may have suitable lugs 29^a bifurcated to receive screws 29^b for securing the member 25 to the lower side of the top frame 10. The flanges 29 and lugs 29^a abut against the top frame. The plate portion 26 95 serves as a flame guard and also provides an attaching bracket for the pipe 26.

Beneath the sockets 18 the end frames 12 are provided with horizontal ledges 30 adapted to support a drip pan 31. Rearward movement of the pan is limited by 105 suitable flanges or stops on the end frames, and the pan may be removed by withdrawing it forwardly off its supporting ledges.

The entire device may be quickly folded or collapsed by removing the burners 20 in the 110

manner indicated in Fig. 4, removing the burner-supporting rod 19 from the sockets 18, withdrawing the drip pan 31, and then swinging the end frames 12 inwardly to the position shown in Figs. 3 and 5, where said end frames abut against parts on the manifold 26. The rod 19, burners 20, and drip pan 31 may then be packed with the body portion into a compact bundle. If desired, the manifold may be detached from the top frame and packed with the other loose parts. The end frames 12 may then be swung up close beneath the top frame.

I claim as my invention:

15. 1. A gas hot plate comprising a top frame provided at each end with spaced apart loop-like bearing members, end frames each having top cross-bars provided with journals mounted to oscillate in said bearing members, means for limiting outward movement of said end frames, a brace rod having its ends detachably engaging said end frames, and one or more burners supported by said brace rod.
20. 2. A gas hot plate comprising a top frame provided at each end with spaced apart loop-like bearing members, end frames each having top cross-bars provided with journals mounted to oscillate in said bearing members, stop lugs carried by said end frames to limit outward movement of the

end frames, said top frame being provided with shoulders against which said end frames abut when in open position, and means for bracing said end frames in open position.

3. A gas hot plate comprising a top frame provided at each end with spaced apart loop-like bearing members, end frames each having top cross-bars provided with journals mounted to oscillate in said bearing members, means for limiting outward movement of said end frames, superposed sockets carried by the inner faces of the end frames, a brace rod constructed to be selectively engaged with said sockets, and one or more burners supported by said rod.

4. A gas hot plate comprising a top frame, end frames pivoted thereto at their upper ends, a brace rod for said end frames, a manifold having a plate portion and a pipe portion, means for detachably connecting said plate portion with the top frame, and one or more burners supported by said brace rod in operative relation with said manifold.

In testimony whereof, I hereunto set my hand in the presence of two witnesses.

GEORGE E. PICKUP.
